UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A MEDICAL CABINET

Application filed January 5, 1932. Serial No. 42,369. Term of patent 14 years.

To all whom it may concern:

Be it known that I, WILLIS O. PROUTY, a citizen of the United States and a resident of the city of Hermosa Beach, county of Los Angeles, and State of California, have invented a new, original, and ornamental Design for a Medical Cabinet, of which the following is a specification, reference being had to the accompanying drawings, forming part thereof, in which—

Fig. 1 is a perspective view of the cabinet

with one side in open position showing my new design;

Fig. 2 is a front elevation thereof;

Fig. 3 is a diagrammatic sectional view of the contour at line 3—3 of Fig. 2; and Fig. 4 is a similar view taken along line 4—4 of Fig. 2.

I claim:

The ornamental design for a medical cabinet, substantially as shown.

WILLIS O. PROUTY.
